UNITED STATES PATENT OFFICE

ALBERT R. BELLEROSE, OF WEST HARTFORD, CONNECTICUT

CURTAIN-ROLLER-OPERATING MECHANISM

Application filed March 28, 1929. Serial No. 350,549.

It is the usual practice to provide curtain rollers with a spring for turning the roller in a direction to wind the curtain thereupon and to provide a ratchet mechanism for releasably holding the roller against rotation under the influence of the spring. This old arrangement is open to various objections, among which may be mentioned the ease with which the arrangement becomes disorganized; the fact that it is often difficult to engage the ratchet mechanism at that point where the curtain is in the desired position; it is frequently necessary to jiggle or vibrate the curtain up and down in order to engage the ratchet mechanism; it is very difficult and sometimes impossible to bring the curtains of the various windows of a room to the same exact level and, since it is necessary to hold the lower edge of the curtain during the operation of rolling the curtain up on the roller, the curtain does not roll up straight. The aim of the present invention is to provide an improved curtain roller operating mechanism wherein the above and other disadvantages and objections incident to structures as now generally used are eliminated. To these ends, I provide an improved arrangement which is characterized by various features of novelty and advantage.

More particularly, an aim of the invention is to provide an improved, simplified, economical and durable structure which may be easily operated.

With the arrangement of the present invention, the curtain may be drawn down to any desired position and then released with the assurance that it will be held in that position, there being no back movement of the curtain whatsoever. Thus, all of the curtains of a room may be drawn down so that their lower edges are all on the same exact line without the necessity of jiggling the curtain or making repeated adjustments thereof. The curtain is automatically wound up by the mere act of moving a lever or the like and, during the upward movement of the curtain, it can be stopped in any desired position by merely releasing the operating or control member. In the act of winding up the curtain, it is not necessary to manu-

ally guide it and there is no danger of the curtain getting out of line and, therefore, it will roll up straight.

Other objects will be in part obvious and in part pointed out more in detail herein-after.

The invention accordingly consists in the features of construction, combination of elements and arrangement of parts which will be exemplified in the construction herein-after set forth and the scope of the application of which will be indicated in the appended claims.

In the accompanying drawings, wherein I have shown, for illustrative purposes, one of the many embodiments which the present invention may take:

Figure 1 is a diagrammatic view showing, in front elevation, a roller having applied thereto a mechanism constructed in accordance with the present invention;

Fig. 2 is a sectional view of the operating mechanism and the curtain roller connected thereto, this view being taken substantially on line 2—2 of Fig. 3; and

Fig. 3 is a side view, with parts broken away, of the operating mechanism.

Referring to the drawings in detail, I have shown, in Fig. 1, for purposes of illustration only, a window having a casing A, a lower window sash B, and an upper window sash C. D is the usual molding which may constitute a guide strip for the lower sash B. E designates the curtain. It is, of course, understood that the parts just described are shown by way of exemplification only, it being evident that my improved mechanism may be used for curtains of various kinds.

The curtain is adapted to be wound upon a roller 10 within which is located a spring 11 which normally tends to rotate the roller in a direction to wind the curtain thereupon. This spring is located within a recess in the roller and encircles a rod 12 on which the roller is journaled, as at 13 and 14. One end 15 of this spring is connected to the rod, and the other end 16 is anchored to the roller. The outer or projecting end 17 of the rod is flat and is adapted to non-rotatably engage in a slot 18 of the usual bracket 19. The

other end of the roller is provided with a polygonal opening, in the present instance the opening being formed by a square sleeve or lining 20.

Located within a casing 25 is a mechanism for holding the roller against rotation. This casing, which may, of course, be of any suitable form, that shown in the drawings being by way of illustration only, is suitably located within the casing A of the window. Journalled in this casing is a shaft 26 having one end projecting beyond the casing, and this projecting end has a fit in the sleeve 20 as shown in Fig. 2. On this shaft is a gear 27 meshing with a pinion 28 on a shaft 29. Fixed to this shaft is a gear 30 which meshes with a pinion 31 on the shaft 32. This latter shaft carries a brake drum 33. The unit (including the shaft 29, the pinion 28 and the gear 30), and which also constitutes a driving connection between the shaft 26 and the brake drum 33, is so supported that when the roller 10 is urged or actually turned in the direction in which the curtain 35 is wound up, the gears 30 and 31 remain in mesh, and, when the roller is turned upon lowering movement of the curtain, the gear 30 is thrown out of mesh with the pinion gear 31. To this end, the reduced projections 34 of the shaft 29 are mounted for movement in arcuate slots 35 which are curved about the axis of the shaft 26.

Co-operating with the brake drum 33 is a brake shoe 36 which is adapted to be disengaged from the brake drum in any suitable manner whenever it is desired to cause the curtain to roll up. In the present instance, this brake shoe is carried by a leaf spring 37 connected as by means of rivets 38, to the bottom wall of the box or casing 25. The rear end of this spring is suitably connected to a control member which is conveniently located at one side and adjacent the sill of the window. In the present instance, this control member is in the form of a lever 40 and has its rear end connected to the free end of the spring 37 by a wire 41. The lever may be pivoted on a pin 42 carried by a member 43 which may be positioned within the window casing A.

The operation of the device is briefly as follows: Normally, the brake shoe is in engagement with the drum 33, and the spring 11 is tending to turn the roller in a direction to wind up the curtain, but the roller is held against such turning movement by the brake mechanism through the gearing within the casing 25. It will be noted that the spring 11 normally tends to turn the gear 27 in the direction of the arrow shown in Fig. 3 so that the unit, including the shaft 29, is held in the position shown in Fig. 3 in which position the gear 30 is in mesh with the gear 31. Assuming now that it is desired to lower the curtain, this may be

done by merely pulling down on the lower edge of the curtain and without, in any way, operating or disturbing the lever 40. When the curtain is thus pulled down, the roller is turned in a counterclockwise direction (referring to Fig. 3) whereupon, due to the engagement between the gear 27 and the pinion 28, the shaft 29 will move rapidly and forwardly in the slots 35, thus disengaging the gear 30 from the pinion 31. When this disengagement takes place, the roller is no longer held against turning movement by the brake so that the curtain may be lowered. When the curtain is lowered, the spring 11 is wound up. It will be observed that, when the curtain is brought down to the desired position and then released, the unit, including the shaft 29, will move back to the normal position shown in Fig. 3, and the brake then becomes effective to hold the curtain in the selected position and there is no backlash so that the positioning of the curtain may be accurately effected. When it is desired to have the curtain go up, it is merely necessary to raise up the forward end of the lever 40, thus withdrawing the brake shoe from the brake drum, whereupon the gears 30 and 27 and the curtain roller are free to be rotated by the spring 11 in the proper direction. Upward movement of the curtain may be instantly stopped by merely releasing the lever 40.

It will be observed that my improved construction is very simple in arrangement, it may be very economically manufactured and installed, and it is extremely durable, there being but few parts and these parts being so constructed and arranged that they are not subjected to wear or the likelihood of disorganization. The curtain may be very easily and conveniently raised and lowered and brought to the desired position.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim as my invention:

1. In combination, a roller on which a curtain is adapted to be wound, means normally tending to turn said roller in a direction to wind the curtain thereupon, means for holding said roller against rotation under the influence of said first mentioned means and

- cluding a rotatable member and a disengageable element adapted to hold said member against rotation, and a connection between said roller and member through which said member holds said roller against rotation under the influence of said first mentioned means when said element is engaged with said member, said connection being automatically disengaged from said member when 5 said roller is turned in a direction to unwind the curtain.
2. In combination, a roller on which a curtain is adapted to be wound, a spring normally tending to turn said roller in a direction to wind the curtain thereupon, brake means for holding said roller against turning movement under the influence of said spring, and a connection between said roller and brake means and including a unit which 10 is normally held by said spring in engaged position with said brake means, said unit being moved to a disengaged position when said roller is turned in a direction opposite to that in which said spring tends to turn said 15 roller.
3. In combination, a roller on which a curtain is adapted to be wound, means normally tending to turn said roller in a direction to wind the curtain thereupon, a brake drum, a brake shoe adapted to be manually disengaged from said drum, and gearing between said brake drum and said roller and including a unit adapted to be thrown into and out of mesh, said first mentioned means normally 20 holding said unit in mesh and said unit being thrown out of mesh when said roller is turned in a direction to lower the curtain.
4. In combination, a roller on which a curtain is adapted to be wound, means normally tending to turn said roller in a direction to wind a curtain thereupon, a rotatable shaft 25 with which said roller is adapted to rotate, a rotatable brake member, a brake shoe normally held against said member, means for disengaging said brake shoe from said member, and gearing between said shaft and brake shoe and including a unit mounted for movement into and out of mesh.
5. In combination, a roller on which a curtain is adapted to be wound, means normally tending to turn such roller in a direction to wind the curtain thereupon, a shaft 30 rotatable with said roller, a brake drum, a brake shoe resiliently held against said drum, a control member for disengaging said shoe from said drum, and gearing between said shaft and drum and including a unit mounted for bodily movement in an arc about said shaft.
6. In combination, a roller on which a curtain is adapted to be wound, a spring normally tending to turn said roller in a direction to wind the curtain thereupon, a shaft 35 rotatable with said roller and having a gear, a shaft having a brake drum and a pinion,
- a brake shoe engaging said drum, and a unit between said gear and pinion and including a shaft mounted for movement in arcuate slots struck about the axis of said shaft, said unit being disengaged from said pinion when 40 said roller is turned in a direction to unwind the curtain.
7. In combination, a roller on which a curtain is adapted to be wound, means normally tending to turn said roller in a direction to wind the curtain thereupon, a rotatable member, an element engageable therewith for preventing rotation thereof, and a connection between said roller and member and including a pair of cooperating parts 45 one of which is movable into and out of engagement with the other, said cooperating parts being automatically disengaged when said roller is turned in a direction to unroll the curtain.
